CLAIM

The ornamental design for a wedge-shaped implant having ridges, as shown and described.

DESCRIPTION

FIG. 1 is an isometric view of a wedge-shaped implant having ridges;

FIG. 2 is a top plan view thereof;

FIG. 3 is a front elevation view thereof;

FIG. 4 is a rear elevation view thereof;

FIG. 5 is an elevation view thereof taken from the right side;

FIG. 6 is an elevation view thereof taken from the left side; and,

FIG. 7 is a bottom plan view thereof.

The broken line showing of the wedge-shaped implant having ridges is for the purpose of illustrating portions of the wedge-shaped implant having ridges and forms no part of the claimed design.
